UNITED STATES PATENT OFFICE

LYDIA LAMPERT, OF CHICAGO, ILLINOIS

BAR SUPPORT AND SPACER

Application filed January 22, 1930. Serial No. 422,609.

The main objects of this invention are to provide an improved bar support and spacer for use in reinforcing systems of concrete construction work; to provide a bar support and spacer having improved means for gripping the reinforcing bars to secure them against accidental displacement; and to provide a device of this kind wherein the separate parts may be made of wire and readily assembled.

An illustrative embodiment of this invention is shown in the accompanying drawings, wherein:

Figure 1 is a fragmentary perspective of one form of the improved device, a mold soffit and a pair of reinforcing bars being also shown.

Fig. 2 is a side elevation of the same.

Fig. 3 is an end elevation of the device shown in Fig. 1, the reinforcing bar being shown in dotted outline.

In the form shown, the reinforcing system involves the use of a plurality of reinforcing bars 1, disposed horizontally in substantially parallel spaced relation above a falsework 2.

The improved bar support and spacer comprises a plurality of supporting members rigidly secured to a wire spacing rod 3 which is adapted to support the bars 1.

The supporting members are also made of wire of a suitable gauge which will insure the necessary rigidity. They are bent to provide supporting feet located below the spacing rod and upstanding arms which frictionally engage the reinforcing bars.

In the form shown, each of the supporting members comprises a single piece of wire 4 having a central portion which provides a horizontal foot or base 5, and a pair of upstanding arms 6, which are spot welded to the spacing rod 3, as shown at 7. The lower portions of the arms 6 are twisted so as to position the base 5 at substantially right angles to the vertical plane of the rod 3.

The upper ends of the arms 6 are arched so as to provide depending fingers 8 which define channels or seats for the reinforcing bars. The fingers 8 are crimped as shown at 9 so as to restrict the channels and render it necessary to force the reinforcing bars into

their seats. The lower extremities of the fingers 8 are free so as to permit the fingers to yield when the reinforcing bars are pressed into their seats.

In operation, the improved devices are placed on the falsework with the spacing rods 3 disposed substantially parallel to one another at the desired intervals. The reinforcing bars 1 are then placed between the yieldable fingers and are pressed downwardly into their seats.

Although but one specific embodiment of this invention has been herein shown and described, it will be understood that certain details of the construction shown may be altered or omitted without departing from the spirit of this invention as defined by the following claims:

I claim:

1. In a device of the class described, a spacing rod adapted to be disposed horizontally for supporting reinforcing bars, and a plurality of wire supporting members arranged at intervals along said rod, each of said supporting members comprising a horizontal base portion intersecting the vertical plane of said rod, both ends of said base being bent inwardly and upwardly to provide a pair of arms connected to said rod and projecting upwardly to define a seat for a reinforcing bar.

2. In a device of the class described, a spacing rod adapted to be disposed horizontally for supporting reinforcing bars, and a plurality of wire supporting members arranged at intervals along said rod, each of said members comprising a base portion intersecting the vertical plane of said rod, both ends of said base being bent inwardly and upwardly to provide a pair of arms welded to said rod, the upper ends of said arms being arched to define seats for the bars, all of said arched portions being located substantially in the vertical plane of said rod.

Signed at Chicago this 18th day of January, 1930.

LYDIA LAMPERT.
